UNITED STATES PATENT OFFICE.

CHARLES ALGERNON PARSONS, OF NEWCASTLE-UPON-TYNE, ENGLAND.

TURBINE.

No. 858,206.

Specification of Letters Patent.

Patented June 25, 1907.

Application filed August 6, 1906. Serial No. 329,444.

To all whom it may concern:

Be it known that I, CHARLES ALGERNON PARSONS, C. B., a subject of the King of Great Britain and Ireland, and residing at

5 Newcastle-upon-Tyne, in the county of Northumberland, England, have invented certain new and useful Improvements in Turbines, of which the following is a specification.

10 This invention relates to steam and like turbines in which the energy of the working fluid is abstracted in a number of stages and is specially directed toward the shaping and arrangement of the blades toward the 15 outlet end of the turbine. In turbines of this class considerable difficulty arises in dealing with the large volume of expanded fluid toward the outlet end or in the lower pressure parts because with the ordinary methods of blading it is necessary to provide long 20 blades in these lower pressure parts so as to give the necessary area of passage for the steam.

The object of the present invention is to 25 enable the use of shorter blades in the lower pressure parts without seriously impairing the efficiency of the turbine.

The invention consists in certain modifications to the cross section combined with an 30 arrangement of the blades at angles decreasing toward the outlet end of the turbine, whereby the velocity of the steam may in the lower pressure parts, be in a considerably greater ratio to the velocity of the blades 35 than in the higher pressure parts. By thus allowing a greater velocity of steam the height of the low pressure blades may be considerably lessened and one of the constructional difficulties involved in turbine manufacture may be avoided with practically no 40 loss in efficiency.

The accompanying diagrams represents copies of impressions taken of the ends of blades actually tried.

45 Figure 1 represents the ordinary arrangement of blades as employed at the high pressure end of the turbine. Fig. 2 represents what I call the "semi-wing" form in which the angle "A" of the blade is slightly less

50 than the angle "A" of the normal form. Fig. 3 represents what I call my "wing" form in which the section and angle are still further modified. Fig. 4 shows a still more marked modification which I call the "double wing" form. The blades in this last case are

at a slightly greater pitch than in the form shown in Fig. 3. Fig. 5 is a section through a turbine provided with blades according to the present invention.

On reference to these diagrams it will be seen that the wing blade is made of flatter section than the type normally employed in the Parsons type of turbines and is very approximately bi-laterally symmetrical about the line X Y in Fig. 3. The width of the 60 blade z may be 15% to 20% or 30% wider in the case of the wing blade than the ordinary blade shown in Fig. 1. The angle A of the blades represents the angle at the discharge side. With this shape of blade the 65 steam instead of being brought to rest relatively at the point of impact and gathering momentum again from the drop in pressure as it flows through the blades—as in the case with the ordinary blades—streams steadily 70 past the blades with high velocity exerting a side thrust upon them on account of the slight curvature of the blade, while its velocity is maintained by the gradual fall in pressure. In Fig. 5 of the accompanying 75 drawings I have shown a section through a turbine provided with blades according to this invention. High pressure steam enters the turbine at the end b, and passes through the blades in the direction shown by the arrow c. Blades included in the dimension line marked d, are of the "normal" form. Those included in the dimension line marked e, are of the "semi wing" form. Those included in the line marked f, are of "wing" 80 form while the blades g, nearest the outlet end h, of the turbine are of the "double wing" form shown in Fig. 4.

Blades according to this invention I call wing blades because the pressure of steam moving at high velocity past them resembles the action of air upon a bird's wings or on an aeroplane. In practice I have found that it is possible to pass three times the volume of steam through these wing blades that is possible with blades of normal openings and angles and of the same weight, the pressure drop through the blades being the same in both cases.

Having now described my invention, what I claim as new and desire to secure by Letters Patent is:—

1. In turbines, rows of blades, at considerable angles to the impinging fluid and bi-laterally non-symmetrical near the high

pressure end of the turbine, rows of blades at lesser angles to the fluid flow and approximately bi-laterally symmetrical near the low pressure end of the turbine.

5. 2. In turbines, rows of blades near the inlet end, set at considerable angles to the impinging fluid and bi-laterally non-symmetrical, successive rows of blades at diminishing angles to the fluid flow, substantially as described.

3. In a turbine in which steam passes through rows of blades in series, rows of blades near the high pressure end, set at

considerable angles to the impinging fluid and bi-laterally non-symmetrical, successive groups of rows (*e*, *f*, and *g*) at decreasing angles to the impinging fluid and approximating to bi-lateral symmetry, substantially as described.

In testimony whereof, I affix my signature 20 in presence of two witnesses.

CHARLES ALGERNON PARSONS.
